UNITED STATES PATENT OFFICE.

KARL HOLTZ, OF BERLIN, GERMANY, ASSIGNOR TO CARL LINDSTRÖM AKTIEN-
GESELLSCHAFT, OF BERLIN, GERMANY.

TALKING MACHINE.

Application filed March 10, 1924, Serial No. 698,204, and in Germany August 17, 1923.

The invention relates to a talking machine of the portable type and to this end is constructed in the smallest possible dimension—without loss of tone quality and loudness—
5 and of minimum weight so that the same may be easily carried about. The lid, by the novel arrangement hereafter described in detail, serves the triple purpose to act as a cover for the talking machine, as a container for the storage of records and as an amplifying horn. This advantage is gained by the subdivision of the lid into one or more compartments formed by foldable or hinged walls by means of which one or more combined sound-amplifying-compartments and record-containing-compartments are effected. These dividing walls may be constructed with side leaves closing the narrow sides of the compartment to form a completely enclosed amplifying chamber.

In giving a detailed description of the construction reference is had to the accompanying drawings of which—

Figure 1 shows a front elevation, the lid (4) in raised position ready for use, showing the complete apparatus enclosing turntable, tone arm and sound box.

Figure 2 shows a vertical section of a side elevation through line $\alpha-\alpha$ of Figure 1.

Figure 3 shows a vertical section through a side elevation as in Figure 2 the machine dismounted for transportation, the lid closed and containing a number of records in the storage compartment.

In the preferred form, box (1) and lid (4) are of equal heights. The body of the box (1) contains the very compact spring motor (2) enclosed in such a way by suitable walls (3) so as to leave a number of small open spaces in the box which serve as containers for parts of the machine, such as winding crank, tone arm and sound box and other accessories which are placed conveniently in such compartments while the apparatus is carried about, or as storage for the accessories when the apparatus is not in use.

Lid (4) is connected by a hinge (5) with the body of the box (1). It may be constructed solid, so that all four sides are in fixed relation to the top leaf of the lid or the sides 11, 12 and 13 may be hinged or in any other way movably or removably con-

nected to the top leaf. The inside centre of the top is provided with a stud (6) over which the records to be stored are arranged. The inner side of the lid (4) is connected by means of a hinge (22) or in any other suitable way to a leaf (7). Said leaf (7) is connected furthermore to the body portion (1) of the apparatus by means of a lid support (8) which maintains the leaf in correct relative position to the latter so that its best possible position for the proper reproduction of sound may be safeguarded whenever the apparatus is in use. The lower part of leaf (7) is provided with an aperture which carries a suitable socket (15) for the universal joint of the tone arm (16) whereas the upper part of the leaf (7) is connected to the main part of the lid (4) by means of suitable stays or hinges (9). Side leaves (10) closing the wedge-shaped tone chamber may be either hingedly connected or inserted into grooves provided in the top (1) and leaf (7) or may be fastened to these parts in any other suitable manner.

The operation of the apparatus is as follows:

After the lid (4) is opened and the leaf (7) in the position provided for by means of the joint (8), the upper part of 7 is connected to 4 by means of the stays (9), the records (14) which may be contained over stud (6) are taken out and eventually the sides (10) are mounted, the tone arm is inserted by means of two pivots (18 and 19) which register with a groove (20) in the ball and socket joint (15), the sound box (17) is connected to the outer end of the tone arm (16) and the apparatus is ready for use. After use the sides (10) are either dismantled or folded into the apparatus the compartment which while in use served as an amplifying horn becomes again the storage for a number of records. It is closed by means of leaf (7) now forming the cover for the record container; sound box, winding crank and tone arm as well as needle container are placed in their respective spaces. The lid is closed and the apparatus ready again to be carried around.

Above description shows only one form of my invention which may be changed in many details without departing from the general spirit of same, whereas the invention

is only limited by the claims here appended.

Having now fully described my invention what I claim and desire to protect by Letters Patent of the United States of America is:

1. In a talking machine, the combination with a base containing a turn table and driving means therefor, of a cover member hinged to the base and comprising a top and 10 sides, a wall movably connected to one of said sides of the cover at the margin thereof, providing the closure of a chamber in the cover member for the reception of records and formed with an opening to receive a 15 connecting member for the tone arm of the machine, and a plurality of substantially triangular walls hinged to the cover member for movement into position transversely thereof to cooperate with the first named

wall and the cover member for converting it 20 into a sound amplifier.

2. In a talking machine, the combination with a relatively shallow base member having a bottom panel and sides and containing a turn table and driving means therefor, of a 25 cover member hinged to the base and comprising a top and sides, the sides being approximately of the same depth as the sides of the base, a wall hinged to one side of the cover member at the margin thereof, means 30 carried by said wall for supporting the tone arm of the machine, and two substantially triangular walls hinged to the cover member for movement into position to cooperate therewith to convert the cover member into a 35 sound amplifier.

In testimony whereof, I affix my signature.
KARL HOLTZ.
